CLAIM

The ornamental design for a pizza container, as shown and described.

DESCRIPTION

FIG. 1 is a perspective view of a pizza container showing our new design;

FIG. 2 is a top plan view thereof;

FIG. 3 is a bottom plan view thereof;

FIG. 4 is a front elevation thereof;

FIG. 5 is a right side elevation thereof, the left side elevation being a mirror image thereof;

FIG. 6 is a rear elevation thereof;

FIG. 7 is a modified form of FIG. 1 in a closed position;

FIG. 8 is a top plan view of FIG. 7;

FIG. 9 is a bottom plan view of FIG. 7;

FIG. 10 is a front elevation of FIG. 7;

FIG. 11 is a right side elevation view of FIG. 7, the left side elevation being a mirror image thereof; and

FIG. 12 is a rear elevation of FIG. 7.
